UNITED STATES PATENT OFFICE.

JAMES H. MILLER, OF PHILADELPHIA, PENNSYLVANIA, ASSIGNOR TO HIMSELF AND CHARLES KRIPS, OF SAME PLACE.

DESIGN FOR A MEDALLION HEAD OF JACKSON.

Specification forming part of Design No. 5,433, dated December 19, 1871.

Specification describing a Design for a Medallion Head of Jackson produced or invented by JAMES H. MILLER, of Philadelphia, Pennsylvania.

The figure in the accompanying drawing fully represents my design, which consists of an alto-relievo medallion head of Jackson facing to the left, the whole being of a character too clearly shown in the drawing to need minute description.

I propose, in most cases, to cast the design in bronze or white metal, of about the size shown, and to mount it upon a black velvet or other dark

ground; but it may be produced in any material and of any desired size.

I claim as my invention—

The design for a medallion head of Jackson, substantially as described, and as illustrated in and by the accompanying drawing.

In testimony whereof I have signed my name to this specification in the presence of two subscribing witnesses.

Witnesses: JAMES H. MILLER.
WM. A. STEEL,
HARRY SMITH.
